DESIGN FOR A SUPPORTING TOWER FOR TANKS OR THE LIKE

Dagbert Ording and Leslie S. Vallely, Houston,
Tex., assignors to Valco, Inc., Houston, Tex.,
a corporation of Texas

Application May 2, 1942, Serial No. 106,780

Term of patent 14 years

To all whom it may concern:

Be it known that we, Dagbert Ording and Leslie S. Vallely, citizens of the United States, residing at Houston, in the county of Harris and State of Texas, have invented a new, original, and ornamental Design for a Supporting Tower for Tanks or the like, of which the following is a specification, reference being had to the accompanying drawing, forming part thereof.

In the drawing:

Fig. 1 is a side elevation of a tower showing my new design.

Fig. 2 is a view similar to Fig. 1 but taken in a direction at 45° to the direction of Fig. 1.

Fig. 3 is a horizontal cross section taken along the line 3—3 of Fig. 1.

The essential feature of our design resides in the formation of panels on the outer faces of the various columns with the upper and lower ends of the panels corresponding in level with the lower and upper surfaces of the beams between the columns.

We claim:

The ornamental design for a supporting tower for tanks or the like, substantially as shown and described.
